UNITED STATES PATENT OFFICE

JAMES DAVIS HUDSON, OF MONTREAL, QUEBEC, CANADA, ASSIGNOR, BY MESNE ASSIGNMENTS, TO MECHANICAL PRODUCTS CORPORATION, LIMITED, OF MONTREAL, QUEBEC, CANADA

HEADLIGHT

Application filed June 25, 1928. Serial No. 288,216.

The invention relates to headlights, as described in the present specification and illustrated in the accompanying drawings that form part of the same.

5 The invention consists essentially of the novel features of construction pointed out in the claims for novelty following a description containing an explanation in detail of an acceptable form of the invention.

10 The objects of the invention are to eliminate the dangers incident to the glaring effect of the headlight of the approaching vehicle, which as is well known produce a blinding effect on the drivers, so much so as to cut out 15 their vision in front for a good distance before and after passing the other vehicle; to insure good projection in the dipped positions of the headlights fully one half the distance of the regular projection of the 20 light, thereby insuring a good driving light even when thrown downwardly and generally to provide a durable and serviceable mechanism for dipping headlights.

In the drawings, Figure 1 is a vertical 25 sectional view of the reflector and its operating parts.

Figure 2 is a rear elevational view of the operating mechanism.

Figure 3 is a perspective detail of the lifting links, levers and rests.

Figure 4 is a side elevational detail of the lifting mechanism in its upper position.

Figure 5 is a side elevational view of the front portion of a motor car, showing the 35 application of this invention thereto, and the headlight in its normal driving position.

Figure 6 is a side elevational view of the front portion of a motor car, showing the headlight in its dipped position.

40 Like numerals of reference indicate corresponding parts in the various figures.

Referring to the drawings, the reflector indicated by the numeral 10 is rigidly secured to a sleeve 11 and to the trunnions 12 and 13 45 at either side of said sleeve, and projecting into the pivot bearings 14 and 15 secured to the frame 16.

The frame 16 is preferably of circular form, though not necessarily so, and may 50 be made with the bridge 17, elevated in the

central portion 18 and carrying on the said elevated portion the solenoid coil 19 and the terminals 20 and 21 of said solenoid.

The core 22 of the solenoid extends downwardly and is a gravity operated core having the slot 23 at its lower end, in which the yoke 24 and particularly the lug 25 is pivotally held by the pivot 26.

55 The bracket 27 is secured to the bottom of the frame and is formed with the upright 29 at its front side reaching towards the centre, the upright 29 carrying the stop 30, which is formed of rubber inserted in the socket 31.

60 The toggles 32 and 33 form the toggle joint 34, and these toggles are in plate form, the toggle 33 being pivotally secured intermediate of its length by the pivot pin 35 to the lower end of the yoke 24, while the same toggle 33 at its rear end is secured to the 65 upright 28, by the pivot pin 36.

65 The other toggle 32 is secured to the reflector 10 below the sleeve 11 by the pivot pin 37, this pivot connection of the toggle 32 to the reflector being in the normal position of the lamp above the toggle joint 34, therefore any downward pressure on the reflector which would tend to dip it, is met by the joint 34, that is to say, the said toggle joint remains on the lower side of the centre 70 between the pivot connections 35 and 37, thereby securely locking the reflector to its best driving position, so long as the solenoid 75 coil remains de-energized.

80 The electric lamp socket 38 containing the electric lamp 39 is slidably mounted in the sleeve 11 and adjusted for focusing purposes by the screw 40 inserted through the lug 41 from said socket and through the lug 42 from said sleeve, thereby moving it forwardly and rearwardly until the proper focus is obtained, of course there is no real novelty about the focusing of the lamp but in the present instance it is done entirely from the inside instead of from the outside.

85 The wire connections 43 and 44 are from the lamp socket 38 and from the terminal 21, and are joined in the armored cable 45, the other terminal 20 is connected to the ground 90 by the connector 46.

The tension spring 47 exerts a slight downward pull on the toggle joint 34 after the said toggle joint has been raised by the energization of the coil 19, thus this spring while not being used as a spring to actually pull the core, it affords just sufficient of a spring pull to relieve any sticking or binding that might occur under very adverse conditions.

10 The wires 43 and 44 in the armored cable 45, lead respectively to the light switch 48 and to the solenoid switch 49, which is here shown as a hand-operated button switch 49, which springs to its return position for the next operation, one operation of the button closing the circuit to energize the solenoid coil 19 and the following operation breaking the circuit to de-energize the solenoid coil 19, consequently this button furnishes a means of operating a rotary electric switch whereby succeeding operations energize and de-energize the solenoid coil alternately.

15 In the operation of this invention, it may be presumed that the car on the highway is travelling at a fair rate of speed, when an approaching car looms up in the distance. As the cars draw together from opposite directions, the button switch 49 is pushed, with the result that the solenoid coil is energized 20 and immediately the core 22 is drawn in the coil, which results in lifting the yoke 24.

25 The lifting of this yoke swings the toggle 33 on its pivot 35, and this raises the toggle joint 34, so that said toggle joint is lifted to its upper position, beyond the centre line between the two pivot connections 35 and 37, and in order that this upper position may be reached the pivot connection 37 is bound to move, and this movement eventually draws 30 on the reflector 10 below its centre, and in drawing on the reflector, the trunnions 12 and 13 rotate in the pivot bearings 14 and 15 and dip the reflector so that it directs the light 35 downwardly.

40 The frame 16 carrying the reflector 10 is inserted in a casing 51, and is preferably cylindrical in form, and this casing at its front end carries the lens 52 and at its rear end the cover 53, which is formed as usual with 45 a fitting 54, through which the cable 45 extends to the switches as explained. The frame 16 is secured in the casing 51 by the screws 50. The casing 51 carries at its front end a visor, 55, which cuts out all upward throw of light in the dipped position of the reflector, therefore, in the operation as described, when the reflector is dipped, the major illumination is towards the roadway, and while there is considerable projection, 55 the visor cuts out the upward throw of the rays in so far as the driver is concerned.

50 What I claim as my invention is:—

60 1. In a headlight, a casing, a dipping reflector pivotally mounted in said casing and having a lamp, a bracket rigidly secured be-

hind said reflector, a stop projecting from said bracket and engaging said reflector in the dipped position thereof, a solenoid coil supported at the upper end of said bracket, a solenoid core, a forked pivot bearing depending from the core, a bar link pivotally secured to said bracket and extending forwardly thereon and pivotally secured toward its forward end in said forked bearing, and a second bar link pivotally secured to the 75 aforesaid first link and to said reflector.

70 2. In a headlight, a casing having a reflector, a sleeve centrally secured to said reflector and forming a support therefor and having a lamp socket projecting therein, a 80 frame within the casing and supported thereby and having a bracket, pivoted toggle joints connecting the bracket and the reflector, an operating yoke pivoted to the toggle joints and forming a journal member for said sleeve, and a solenoid supported within the casing and having a core controlling the yoke.

75 Signed at Montreal, Canada, this 31st day of May, 1928.

JAMES DAVIS HUDSON.
